BLOCK-GROOVING MACHINE

Application filed May 27, 1927. Serial No. 194,742.

Our invention relates to improvements in block grooving machines and the object of the invention is to devise an improved machine which will cut out a groove of the required shape in one face of the block.

A further object is to devise a machine which can be so operated that the grooves cut in the blocks will be uniform and clean cut.

10 While our invention is particularly intended for cutting the grooves in wheel or chock blocks adapted to be placed against the tires of automobiles being shipped in freight cars in which the blocks are secured to the floor 15 of such car, our machine is susceptible for use for many other purposes in which it is desired to cut an arc shaped groove in the face of a block.

Our invention consists of a block grooving machine constructed and arranged all as 20 hereinafter more particularly described and illustrated in the accompanying drawings in which:—

Fig. 1 represents a plan view of the machine.

Fig. 2 is a vertical cross section through the line 2—2 Figure 1.

Fig. 3 is a side elevation of the cutter head.

30 Fig. 4 is a front elevation thereof.

Fig. 5 is a side elevation of the block which it is desired to groove, showing the groove in dotted lines, and

35 Fig. 6 is a plan view of the block showing the groove cut therein.

Like characters of reference indicate corresponding parts in the different views.

1 is the base of the machine and 2 is the bed plate upon which are mounted the bearings 3 and 4. 5 is the cutter head shaft journaled in the bearings 3 and 4 and carrying at one end the cutter head 6 and at the other end the coupling 7 which connects the shaft 5 to a drive shaft 8 adapted to be driven 45 by any source of power.

9 is a carriage pivotally mounted on the vertical shaft 10 so as to be capable of swinging in a horizontal plane, said carriage 9 comprising a frame-like structure including the 50 transverse members 11 and 12, the former

having a longitudinal slot 13 through which the shaft 5 extends. A brace 14 extends between the upper faces of the members 11 and 12, and an arc shaped plate 15 extends between the lower faces of such members. 55

16 is an adjustable notched plate on the plate 15, the notch 17 thereof adapted to receive a corner of the block 18 to be grooved, said block in the present instance being of trapezoidal section. 19 is a gauge plate of 60 L-section also secured to the upper face of the plate 15 against which the lower edge of the surface of the block to be grooved engages. 20 is a flap hinged to one edge of the brace 14 and provided with the handle 21, 65 said flap 20 being provided on its lower face with a pin 22 which is adapted to engage the upper face of the block 18, when the flap is in the block engaging position. 23 is a spring extending between the flap 20 and any portion of the carriage as for instance the collar 24. 70

25 is an operating handle extending outwardly from the arc shaped plate 15 and preferably positioned immediately below the handle 21 so that both handles may be 75 grasped in one hand by the operator of the machine.

The face of the cutter head 6 remote from the shaft 5 is conical in shape and carries the 80 triangular cutter knives 26 secured thereto by the bolts 27. 28 are adjustable lead knives inserted into the cutter head on its periphery.

Referring to Figures 5 and 6 of the drawing 29 represents the groove cut in the face 30 85 of the block 18 and, as will be seen, this groove is arc shaped in longitudinal section, the radius of the arc exactly corresponding with the periphery of the tire of the automobile with which it is desired to engage. In cross 90 section the groove 29 is also arc shaped to correspond with the cross sectional curvature of the automobile tire.

We will now describe the operation of our machine. 95

The block 18 is placed on the plate 15 and the plate 16 suitably adjusted so that the block is in the required position. The flap 20 which is normally spring held by the spring 23 in the position illustrated in Figure 2 is pulled 100

down by the handle 21 until the pin 22 engages the upper face of the block. The operator then grasps the handles 21 and 25 and swings the carriage 9 toward the cutter so that the face 30 of such block 18 bears against the cutter knives 26 with the result that as the carriage is pushed farther over into the position illustrated in dotted lines in Figure 1 a groove as above described is cut in the face 30 of such block 18.

10 To remove the block from the machine it is only necessary to lift the flap when the block may be withdrawn and the carriage can then be swung back into its initial position ready for the cutting of another block.

15 From the above description it will be apparent that we have constructed a very simple and effective machine which will operate with a cutter head which while revoluble is not otherwise moved, the block to be cut being fed thereagainst, thus avoiding the complicated mechanism required in machines, such as shapers, used for this purpose. Furthermore, we have devised a machine in which 20 the block can be readily inserted thereinto and withdrawn therefrom with the minimum of trouble and also in which the groove cut in successive blocks will be uniform.

25 What we claim as our invention is:

30 In a block grooving machine, a revoluble cutter fixed in position, a swingable block carrying carriage comprising spaced apart transverse members, a lower block supporting member secured at its ends to the transverse members, an upper member extending 35 between the transverse members, a hinged flap normally springheld in its upwardly swung position, an operating handle on the lower block supporting member, and a handle 40 on the hinged flap located substantially above the operating handle.
